ALTERNATING CURRENT ALARM

Albert Kvaal, Oslo, Norway, assignor to A/S Elektrisk Bureau, Oslo, Norway

Application December 26, 1930, Serial No. 504,894
In Norway December 31, 1929

6 Claims. (Cl. 177—7)

The present invention relates to an alternating current alarm, wherein the armature is suspended in a simple manner.

An essential feature resides in the armature being supported by means of two pair of knife edges enabling a very easy tilting of the armature, which is made in the form of a plate constituting the counter-parts of the said edges. The armature support is made as a spring having a longish aperture, through which projects an eccentric portion of a turnable screw. When this is turned, the said spring is raised or lowered thereby adjusting the armature vertically relatively to the electromagnet cores. When at rest the armature is retained in contact with one of the magnet cores either by spring action or by a magnetic momentum produced by a permanent magnet forming part of the alarm.

The invention is illustrated in the accompanying drawing, wherein Fig. 1 is a side view, partly in section, showing the alarm magnets with the adjustable armature suspension. Fig. 2 is a sectional view on a plane perpendicular to that of Fig. 1. Fig. 3 is a perspective view of the armature suspension drawn to a larger scale.

1 and 2 are the magnet coils, 3 and 4 the two legs of a horse-shoe shaped core. From the end portion of the core a vertical lug 5 is stamped out serving to carry the armature support 6, 7, 8. 30 This consists of two magnetic steel plates 6, 8 and an intermediate non-magnetic spring 7. These parts may be connected together by a rivet 9.

The support is suspended on an eccentric portion 10 of the stem of a screw 11 having an adjustable head 12, a clamping nut 13 and a springy washer 14 enabling a turning of the screw by means of the head 12 without any loosening of the nut 13 from the screw.

40 At its lower part the plate 8 is cut out as shown at 15 enabling the central end portion 16 of the spring 7 to be bent laterally. The lowermost portion of the spring 7 is extended into a T-shape as indicated at 17. Thereby the lateral extensions of the portion 17 may constitute lower knife edges 21 serving to carry the armature plate 24. This is an important feature of the invention enabling a very easy tilting motion of the armature.

50 The spring 7 forms lateral legs provided at their lower ends with laterally extended portions 18, 19 of such a shape as to constitute at their upper edge supporting edges 22 for a supporting plate 20 serving to retain the coils 1 and 2 in position. The extensions 18, 19 form at their

lower part upper knife edges 23 for the tilting armature plate 24, which is consequently, as will be seen, supported tiltingly by two pairs of knife edges 21 and 23. The extensions 18, 19 are also provided with guiding pins 25, 26 projecting down through holes 27, 28 made in the armature plate 24. From the armature plate there are stamped out central transverse lugs 29, 30 upon which the edges 21 have its tilting contact. The clapper 32 which co-operates with the bell cups 33 is supported by the clapper stem 31 made integral with the plate 24.

When the spring 16 is bent to the side through the slot 15 and the armature plate 24 is tilted after inserting the pins 25, 26 in the holes 27, 28 the supporting knife 17 of the spring may be inserted without difficulty below the lugs 29, 30. When the spring is returned to its vertical position the armature will be secured on the knife edges thus that it may tilt freely.

In order to obtain a perfect tilting action of the armature, the knife edges 21 and 23 are in alignment with each other. Further, it is necessary that by a turning of the screw 11 the armature support 6, 7, 8 be adjusted vertically only. For this purpose the eccentric screw portion 10 engages the support through a longish hole 34 in the parts 6, 7, 8.

It will be seen that the most parts of the alarm described may be formed by stamping or pressing. Consequently, it will be cheap in manufacture and may be easily assembled, because the spring portion 16 may be bent to the side and in such a position be introduced under the lugs 29, 30.

The tilting support enables a very easy motion of the armature. Moreover, the alarm may be easily adjusted and will operate perfectly in spite of its simple construction.

What is claimed is,

1. An alternating current alarm comprising magnet cores, electromagnetic coils thereon, a tiltable magnet armature disposed below and in operative relation with said cores, an armature-supporting and mounting member disposed in fixed relation to said cores and having a spring mounting portion extending at right angles to the armature and capable of being bent laterally so that the armature can be fitted thereover and provided with armature-supporting edges, portions disposed in fixed relation to the cores and provided with counter-edges in alignment with the said supporting edges, the armature being so formed on one side with portions cooperating tiltingly with the supporting edges and on the op-
